W. C. BRUNKE,
COMBINED SPARK PLUG AND SPARK GAP.
APPLICATION FILED JUNE 25, 1917.

1,241,339.

Patented Sept. 25, 1917.

UNITED STATES PATENT OFFICE.

WILLIAM C. BRUNKE, OF OMAHA, NEBRASKA, ASSIGNOR TO EFFICIENCY MOTOR-DEVICE CORPORATION, OF OMAHA, NEBRASKA.

COMBINED SPARK-PLUG AND SPARK-GAP.

1,241,339.

Specification of Letters Patent. Patented Sept. 25, 1917.

Application filed June 25, 1917. Serial No. 176,665.

To all whom it may concern:

Be it known that I, WILLIAM C. BRUNKE, a citizen of the United States, residing at Omaha, in the county of Douglas and State of Nebraska, have invented certain new and useful Improvements in Combined Spark-Plugs, and Spark-Gaps, of which the following is a specification.

This invention relates to a combined spark plug and spark gap, and has for one of its objects to provide an intensifier for a spark plug which will include a metallic threaded part for the base of its insulating dome for a mounting on the ground electrode to avoid the usual formation of threads in the dome. Another object is to provide a mounting for the central electrode which will permit convenient assemblage of parts, will conduce to convenience in manufacture and will prevent any movement of gases through the spark plug without the use of gaskets. Another object is to provide an adequate support for sustaining stresses when pressing the tapered central electrode to its seat. Still another object is to provide an annular chamber in combination with a tapered electrode of such form that the ignited charges of hydrocarbon will prevent any accumulation of soot at the inner, exposed, base of the tapered central electrode, to prevent short circuits of the electrical charges.

With the foregoing objects in view the invention presents a novel construction combination and arrangement of parts as described herein and claimed, and as illustrated in the accompanying drawing, wherein,—

Figure 1 is a view of the device in side elevation. Fig. 2 is a view of the same in longitudinal section. Fig. 3 is a transverse section on line 3—3 of Fig. 4. Fig. 5 is a side view, partly in section, of the dome. Fig. 6 is a side view partly in section, of the insulating jacket. Fig. 7 is a side view of the central electrode. Fig. 8 is a plan view of the metallic, threaded base of the insulating dome, its upright flange being in transverse section. Fig. 9 is a transverse section through the metallic base of the dome.

Referring now to the drawing for a more particular description, the conventional metallic housing or ground electrode for the spark plug is indicated at 10, the usual cylindrical chamber opening on its inner end being indicated at 11.

At 12 is indicated a dome constructed of insulating material, provided midway between its top and bottom with eight apertures 13, and having embedded therein, near its top, a metallic reinforcing-block 14, said block being for the purpose of providing a threaded connection with a comparatively short metallic rod or electrical conductor 15, the block having a threaded aperture, and the upper part of the dome having suitable apertures for receiving said conductor.

The metallic housing 10 is provided at its inner end with an upright, exteriorly threaded, annular flange 16, and therefore forms a recess, circular in plan, indicated at 17. The lower end of the dome is provided with an interiorly threaded metallic base or nut 18 adapted to be mounted on the flange 16, said base being provided with an upright annular flange 19 having apertures 20 formed therein and at the time of molding the dome the insulating material of the dome becomes embedded in the apertures 20 as a holding means so that the metallic base and dome will be firmly connected; and it will be noted that the required threaded connections for the dome, mentioned, are metallic parts, this being a desired feature of construction since, otherwise, the insulating material employed would soon become worn and the dome would be subject to vibration during operation.

Numeral 21 indicates a tapered metallic electrode circumscribed throughout its entire length by an insulating jacket 22 of mica, its end of greatest diameter provided with a projection 23, said tapered electrode having a length greater than the housing 10 and its flange 16, and having a sufficient length to project within the dome, its end of greatest diameter being disposed adjacent to the open end of the chamber 11, said housing 10 being provided with a tapered base for receiving said electrode and its jacket. The projection for the ground electrode for coöperation with the projection 23 as indicated at α .

At 24 is indicated a tapered sleeve or hollow cylinder of insulating material adapted to be disposed to circumscribe the upper ends of the electrode 21 and its mica jacket. Numeral 25 indicates a metallic nut having a threaded connection with the end of the electrode 21, and in effect, operating as an electrical conductor therefor.

When assembling the parts the nut 25 may be rotated to cause a pressure of the electrode 21 and its mica jacket within the tapered aperture of the housing 10 so that no gaskets will be required for preventing an outward movement of gas from the engine and providing a very rigid mounting for this electrode for resisting stresses occasioned by the ignited charges of gas during operation, the mica jacket 22 being depended upon for insulation.

It will be seen that the truncated hollow cone or tapered sleeve 24 bears upon the inner end of the ground electrode to provide insulation for the nut 25, and on account of its form sustains stresses to advantage and provides a support for the nut in alignment with the apertures 13 so that the jump-spark may be seen.

On account of the tapered form of the electrode 21 and its jacket 22, in conjunction with the form of the cylindrical chamber 11 it will be seen that when the parts are assembled, an annular space is formed between the jacket and the adjacent wall of the ground electrode said annular space having a greater volume at the inner end of the chamber 11 than at the outer end of the jacket, and this is desirable to prevent an accumulation of soot in said annular space and particularly at the end of the jacket, to prevent short circuits. It is considered that, during operation, each ignition of gas will cause the exhaust gases to move outwardly of the chamber 11 with greater force than ordinary on account of the constricted part adjacent to the end of the jacket which prevents the soot from adhering to the end of the electrode 21.

Having fully described my invention, what I claim and desire to secure by Letters Patent is:—

1. In devices for the purposes described, an elongated, metallic plug having a cylindrical chamber opening on its outer end and an annular flange projecting beyond its inner end, a tapered electrode longitudinally traversing the plug, its part of greater divergence being disposed in said chamber and its part of lesser divergence being disposed centrally of and projecting beyond the end of said annular flange, an insulating jacket disposed within said plug and circumscribing the electrode, a tapered insulating-sleeve mounted on the plug and circumscribing the insulating jacket, an electrical conductor bearing on the insulating sleeve and having a threaded connection with the electrode, an

insulating dome having sight-apertures in its sides and having a metallic base for a threaded connection with the annular flange of said plug, and an electrical conductor mounted for longitudinal adjustments in the dome to provide a spark gap substantially in line with the sight-apertures of said dome. 65

2. In devices for the purposes described, an elongated, metallic plug having a cylindrical chamber opening on one of its ends and having an annular flange projecting beyond its opposite end, a tapered insulated electrode longitudinally traversing the plug, its part of greater divergence being disposed in said chamber and its part of lesser divergence being disposed centrally of and projecting beyond the end of said annular flange, a tapered insulating-sleeve mounted on the plug and circumscribing the insulated electrode, a metallic part bearing on the insulating sleeve and having a threaded connection with the insulated electrode, an insulating dome having sight-apertures and having a metallic base for a threaded connection with the annular flange of said plug, and an electrical conductor mounted in the dome to provide a spark gap adjacent to the sight-apertures of said dome. 75 80

3. In devices for the purposes described, a metallic plug having a cylindrical chamber opening on one of its ends and having an annular flange projecting beyond its opposite end, a tapered electrode longitudinally traversing the plug, its part of greater divergence being disposed in said chamber and its part of lesser divergence being disposed centrally of and projecting beyond the end of said annular flange, an insulating jacket disposed within said plug and circumscribing the electrode, an insulating-sleeve mounted on the plug and circumscribing the insulating jacket, a metallic element bearing 100 on the insulating sleeve and having a threaded connection with the electrode, a dome provided with a sight-aperture and having a part threaded on the annular flange of said plug, and an insulated electrical conductor 105 mounted for longitudinal adjustments in the dome to provide a spark gap in combination with the metallic element on said insulating sleeve, said spark gap being disposed adjacent to the sight-aperture of the dome. 110

In testimony whereof I have affixed my signature in presence of two witnesses.

WILLIAM C. BRUNKE.
